CLAIM

The ornamental design for a partition screen, as shown and
described.

DESCRIPTION

FIG. 1 is a perspective view showing a front, top and side of
the partition screen of the present invention;

FIG. 2 is a front elevational view of the partition screen, the
rear elevational view being a mirror image thereof;

FIG. 3 is an elevational view of a first side of the partition
screen, the opposite side elevational view being a mirror
image thereof;

FIG. 4 is a top plan view of the partition screen; and,

FIG. 5 is a bottom plan view of the partition screen.
